UNITED STATES PATENT OFFICE.

JESSE COBB, OF LAREDO, TEXAS.

CRATE.

1,427,193.

Specification of Letters Patent. Patented Aug. 29, 1922.

Application filed July 27, 1921. Serial No. 487,840.

To all whom it may concern:

Be it known that I, JESSE COBB, a citizen of the United States, and resident of Laredo, in the county of Webb and State of Texas, have invented certain new and useful Improvements in Crates, of which the following is a specification.

This invention relates to crates especially adapted for receiving vegetables and fruit though not necessarily restricted to such use.

An important object is to provide a folding crate having novel means whereby the same may be readily and conveniently collapsed for return shipment.

15 A further object is to provide a folding crate having corner posts of considerably greater strength than the side slats so that the crate is enabled to withstand the hard usage to which it is subjected when being filled and when being transported.

20 A further object of the invention is to provide a folding crate which is of highly simplified construction, efficient in use and cheap to manufacture.

25 Other objects and advantages of the invention will be apparent during the course of the following description.

In the accompanying drawing:

Figure 1 is a perspective of the improved 30 crate open.

Figure 2 is a perspective of the body of the crate collapsed.

Figure 3 is a perspective of a cover of the crate.

35 Figure 4 is an end elevation of the crate.

Figure 5 is a perspective of a pivot pin embodied in the invention.

In the drawing the numerals 5 designate the sides which consist of upper and lower 40 pairs of spaced side bars 6 between which slats 7 are secured by means of fastening devices 8. As illustrated in Figure 1 the side bars 6 are extended beyond the spaced slats 7 and are rigidly secured to the reduced terminal portions 9 of corner posts 45 10 by means of fastening devices 11 which may be in the nature of nails or the like. The outer sides of the corner posts 10 are flush with the outer sides of the side bars 50 6 so as to present a neat appearance and so as to provide the strength necessary to enable the crate to withstand hard usage.

The end walls consist of cross bars 13 having connection with spaced parallel slats 55 14, the said end walls being arranged inwardly of the ends of the side walls and

protected thereby. With reference to Figures 1 and 4 it will be observed that U-shaped pivot pins generally designated by the numeral 15 pivotally connect the end 60 walls to the end portions of the side walls and the said U-shaped pins are provided with branches 16 having pivotal connection with the extended end portions of the cross bars 13. Heads 17 are formed on the 65 branches 16 and serve to prevent the removal of the branches 16 from the cross pieces 13. Each pivot pin 15 is also formed with a bight portion 18 which extends through the adjacent terminal portion of 70 the adjacent side bar 6 and thereby connects the end wall to the side walls in such a manner that the walls may partake of movement with relation to each other when it is desired to open the crate or when it is 75 desired to collapse the same. Further the pivot elements 16 are provided with short branches 20 arranged in spaced parallel relation to the branches 16 and lying flatly in contact with the outer sides of the side bars 80 6. It is understood, of course, that the branches 20 are formed by bending the terminal portions of the pivot pins 15 after the same have been passed through the terminal portions of the side bars. 85

The pivot pins 15 are also employed as a means for connecting cross beams 22 to the terminal portions of the side bars 6, the said cross beams being arranged in spaced relation to the end walls and being extended beyond the surfaces of top and bottom walls or covers 24 to prevent the covers from coming in contact with the ground or other support for the crate. Further the cross beams 22 which extend outwardly from the covers 90 24 prevent crates or other objects which may rest upon the crate forming the subject matter of this application from contacting with and possibly breaking the cover 24.

Each wall or cover 24 is composed of a 100 plurality of spaced parallel yieldable slats 25 joined by cross strips 26, the said cross strips being extended beyond the outermost slats 25 and adapted to contact with the longitudinal edges of the side walls. One 105 end of each cover 24 is provided with a cross strip 27 which terminates flush with the outer edges of the outermost slats 25 and thereby permits that end of the cover to be forced downwardly between the adjacent 110 cross beam 22 and the adjacent end of one of the end walls. When the narrow end of

the cover 24 is inserted between the cross beam 24 and the adjacent end wall the other ends of the slats may be positioned between the opposite cross beam and the opposite end wall and subsequently confined between the beam and the end wall. In other words when it is desired to apply the cover 24 it is merely necessary to slide the narrow end of the same between one of the beams 22 and 10 the adjacent end wall a sufficient distance to permit the opposite end of the cover to be forced downwardly and rearwardly between the opposite beam and the opposite end wall. When thus positioned the cover 24 is securely 15 held in position and the crate is effectively held against collapsing. However in order to properly position the cover 24 the slats 25 must be capable of yielding slightly. With 20 reference to the foregoing description it will be apparent that a crate constructed in accordance with this invention may be readily collapsed for occupying but a small amount of space during return shipment. By reason of the particular means employed for 25 connecting the sections the crate is enabled to withstand the strains to which the same is subjected during use.

I claim:

1. A crate having side walls, end walls 30 arranged between and inwardly of the ends of the side walls, U-shaped pivot pins having branches extending through said end walls and having connecting portions extending through the end portions of the side walls, 35 said pivot pins also being provided with branches flatly engaging the outer sides of the side walls, and cross beams arranged at the ends of said side walls and projecting beyond the longitudinal edges of the same to 40 form rests.
2. A crate having side walls, end walls arranged between and inwardly of the ends of the side walls, U-shaped pivot pins having 45 branches extending through said end walls and having connecting portions extending through the end portions of the side walls, said pivot pins also being provided with branches flatly engaging the outer sides of the side walls, cross beams arranged at the ends of said side walls and projecting 50 at the ends of said side walls and projecting

beyond the longitudinal edges of the same to form rests, and covers having their end portions confined between said cross beams and the end walls, said covers being arranged inwardly of said cross beams and 55 protected thereby.

3. A crate having side walls, end walls arranged between and inwardly of the ends of the side walls, U-shaped pivot pins having branches extending through said end walls and having connecting portions extending through the end portions of the side walls, said pivot pins also being provided with branches flatly engaging the outer sides of the side walls, cross beams arranged at the 60 ends of said side walls and projecting beyond the longitudinal edges of the same to form rests, and covers having their end portions confined between said cross beams and the end walls, said covers being arranged inwardly of said cross beams and 65 protected thereby, said cover being provided with a plurality of yieldable slats arranged between said side walls and having connecting strips contacting with the edges of said side walls, each cover also being provided with a cross strip terminating at the outer 70 edges of the outermost slats.

4. A crate comprising side walls inclusive of pairs of spaced parallel side bars and 75 spaced slats arranged between said side bars, the ends of said side walls being provided with corner posts having reduced terminal portions secured between the terminal portions of said side bars, and end walls pivoted to said side walls and arranged inwardly of the ends of the same.

5. A crate comprising side walls inclusive of pairs of spaced parallel side bars and 80 spaced slats arranged between said side bars, the ends of said side walls being provided with corner posts having reduced terminal portions secured between the terminal portions of said side bars, end walls pivoted to 85 said side walls and arranged inwardly of the ends of the same, and cross beams secured to the ends of said side walls in spaced relation to said end walls.

JESSE COBB.
